UNITED STATES PATENT OFFICE.

CLARENCE E. LOMAX, OF CHICAGO, ILLINOIS, ASSIGNOR, BY MESNE ASSIGNMENTS,
TO AUTOMATIC ELECTRIC INC., OF CHICAGO, ILLINOIS, A CORPORATION OF
DELAWARE.

REGISTRATION SYSTEM.

Application filed June 8, 1925. Serial No. 35,834.

This invention relates in general to registration systems of the type in which the patrolman in making his rounds reports his whereabouts to the central station by operating the mechanism of reporting stations which are distributed over his route.

Specifically the invention relates to improvements in the equipment and circuits of such a system, which reduces the installation and maintenance cost thereof without impairing the reliability and usefulness of the system.

In the well known registration systems, in use prior to my invention, a number of reporting stations are grouped together on one line, and that line leads to the central station and terminates on reporting mechanism individual to it. In my invention I have departed from the well known systems of this type by terminating such reporting station lines on individual switches at the central station. I have provided a relatively small number of registering devices operable by a control switch which is accessible to the switches on which the lines terminate.

Accordingly one of the objects of my invention is to provide a new register control mechanism that is accessible to and operable from all of the reporting stations to actuate the registers to visually indicate from which reporting station the call has been sent.

A further object of my invention is to provide a pen register mechanism associated with and individual to the register control switch, this pen register mechanism being operated simultaneously with the control switch to permanently register the number of the reporting station.

A further object of my invention is to provide a means enabling the central station attendant to listen in on any call irrespective of the line or station from which it comes, to supervise and direct the patrolman.

A further object of my invention is to provide a means enabling the central station attendant to connect with any line in the system, to signal out on that line to call the patrolman to a reporting station, and to provide talking circuits so that the central sta-

tion attendant may converse with the patrolman to give him directions and instructions.

Further objects of my invention which are not specifically enumerated herein will be apparent from the specification and claims which follow. The drawings comprising Figs. 1 and 2 when arranged with Fig. 2 to the right of Fig. 1 with the correspondingly numbered lines in alignment, show sufficient details of the equipment to permit a clear understanding of my invention.

In Fig. 1 are shown a plurality of reporting stations A, B, and C, which are connected to the central station over the line conductors 7 and 8, which lead through the keys K¹ and K² and terminate on the line switch R which is individual to that line. This line switch R is of the well known plunger type line switch of the automatic telephone system and is explained in detail in the book automatic telephony by Smith and Campbell on pages 44 to 50 inclusive. Associated with the line switch R is a master switch, not shown, which cooperates with the line switch enabling it to perform its functions. The master switch is well known being explained in the above reference and the circuits of a typical line switch and master switch installation being shown in Fig. 46 on page 48 of the reference. Briefly the master switch and line switch cooperate to keep the plunger of the line switch standing opposite the terminals of an idle trunk such as the trunk 13 to 16 inclusive leading to the control switch C of Fig. 2. When a call is initiated by the line to which the switch R is individual, the switch operates to drive the plunger, not shown, into the bank closing the contacts 57 to 60 so that they make contact with the trunk terminals 13 to 15 inclusive. Fig. 1 also shows the desk equipment DE comprising keys K³ and K⁴, relays 20-23 inclusive and the associated apparatus, this desk equipment being common to the plurality of lines terminating at the central station. By means of keys K¹ and K² this desk equipment may be connected with the line in a manner which will be explained in detail hereinafter.

Fig. 2 shows the control switch C which is accessible to any line in the system through the medium of the line switch individual to that line. The control switch C may be of the well known Strowger type vertical and rotary motion switch, such as is shown in the Patent 815,176 issued March 13, 1906, to Keith, Erickson and Erickson, with the circuits modified in accordance with the objects of this invention. The control switch is operable from the reporting station to step the wipers 171 and 173 into engagement with the bank contacts such as 194-196 inclusive, to light the signal lamp such as 177 to visually indicate the station from which the report is received. Associated with the control switch, is the pen register PR, which is individual to the control switch and operated simultaneously with it to permanently record the number of the reporting station.

In the installation of such a registration system it may be necessary to provide a plurality of control switches, such as C, to receive the patrolman's reports. All of these switches are available to the line switch R and all have access to the signal, such as 177, the latter being multiplied from switch to switch in the well known manner. Each control switch has its individual pen register to record the code numbers of the stations reporting through that switch.

Associated with the control switch trunk, is the key K^s enabling the central station attendant to connect the transmitter 117 and the receiver 119 into the trunk circuit, thereby enabling him to converse with the patrolman making the report, irrespective of the station from which the report is coming. The central station is also equipped with the night alarm signal circuit NA which is common to all the control switches and which operates whenever a call is received at the station.

In order to simplify the drawing I have shown a plurality of batteries, whereas in the installation there would be but one battery, preferably with its positive pole grounded. While I have chosen to show my invention in connection with a specific type of equipment, I have done so merely by way of example and am not to be limited by the specific disclosures shown herein.

Having thus described my invention in general, I will now proceed with a detailed description of its operation, when the patrolman calls in to report from a reporting station.

Station A consists of a telephone associated with the standard patrolman's pull box, such as is well known and in common usage in such systems of the present day. The patrolman making a call from station A removes the receiver 1 from the switch-hook 3 thereby disconnecting a signalling circuit which includes the signal lamp 62

and the condenser 64, and closes in its place the talking circuit which includes the transmitter 2, the induction coil 4 and the receiver 1. The operation of the hook switch closes the contact 3 thereby closing a circuit 70 which is traceable from ground through spring 55 of the individual switch R over conductor 11 through spring 39 and its break contact, conductor 9, through spring 34 and its break contact, line conductor 7, 75 through the transmitter 2, one winding of the induction coil 4 impulse springs 6', hook switch 3 and its make contact, line conductor 8, through spring 31 and its break contact, conductor 10, through spring 33 and 80 its break contact, conductor 12, through spring 56 and its break contact through the winding of relay 17 to grounded battery. Relay 17 energizes and at spring 54 closes a circuit traceable from ground through 85 spring 54, through the winding of magnet 18 to open main battery. Magnet 18 energizes over this circuit and operates to cause the plunger, not shown, to close the contacts 57 to 60 inclusive, thereby closing a circuit 90 to the control switch C which is traceable; from ground through the lower winding of relay 101 of the control switch C conductor 15 through bank contact 60, line conductor 11 thence over the previously traced circuit 95 through the reporting station A to line conductor 12 through the spring 57 line conductor 13 through the upper winding of relay 101 to grounded battery. Relay 101 energizes and closes a circuit from ground through spring 133 and its make contact 100 through the winding of relay 102 to grounded battery. Relay 102 energizes and at spring 135 closes a circuit from ground through spring 135 and its make contact, conductor 14, bank contact 58 through the winding of magnet 19 to grounded battery. Magnet 19 energizes over the circuit and functions to hold the plunger, not shown, 105 in its operated position. When the magnet 18 energizes it opens the previously traced circuit to the line relay 17 at springs 55 and 56, the line relay 17 being slow to release because of the copper slug on its core remains in energized position for a brief interval after the circuit through its coil has been opened. This interval is long enough to permit the energization of magnet 19 before the line relay 17 detacts its armature and opens the previously described circuit 115 of magnet 18. Relay 102 upon energizing closes the obvious circuit to signal lamp 190 which includes the springs 136. This signal light will notify the central station attendant that a call is coming in on the control switch C. Relay 102 at springs 134 also prepares the impulsive circuit which will be explained hereinafter.

The equipment is now ready to receive 125 the report from the station A. The cam IC 130

of the control box associated with the station A is arranged to send out the digits 2, 4, 2, that being the number assigned to the station. The patrolman will then pull the box 5 in the well known manner causing the impulse cam IC to revolve in the direction indicated by the arrow, bringing the teeth of the cam between the impulse spring 6' to open the above traced circuit for the relay 101 a 10 number of times corresponding to the digit being transmitted. While the impulse cam is off normal, the shunt springs 6 are operated, to shunt out the transmitter and winding 4 of the induction coil, thereby preventing 15 objectionable clicking in the receiver 1 as the impulses are sent. Relay 101 falls back each time the circuit is opened at the impulse spring 6' and opens the circuit of relay 102, which, being slow to release because of 20 the copper collar on its core, remains in energized position. Relay 101 on falling back closes a circuit traceable from ground through spring 133 and its break contact, through spring 134 and its make contact, 25 thence over two paths in parallel, one over conductor 165, through the winding of the magnet 112 of the pen register PR to grounded negative battery; and the other through spring 138 and its break contact, 30 through the winding of relay 104, over conductor 166, through the winding of auxiliary switch motor magnet 110, to grounded negative battery. Magnets 110 and 112 energize and deenergize with the impulses received. 35 Relay 104 energizes on the first impulse and, being slow to release because of the copper collar on its core, remains energized during the impulses. In case of the report from station A, the first digit sent would consist 40 of two impulses which would operate the pen register 180 to mark the digit 2 on the recording tape 181 in the well known manner. The auxiliary switch S would be stepped by the magnet 110 so that its wiper 45 147 and 148 are in engagement with the second bank contact. After the second impulse has been received, the cam IC allows the impulse spring 6' to remain in contact for a longer interval than during 50 the transmission of the first digit, during which time the relay 104 restores, its circuit being held open by the relay 101. When relay 104 restores it closes a circuit traceable from ground, through springs 135 through 55 springs 139, through the wiper 147 now in engagement with the second bank contact, conductor 164, through the winding of relay 103 to grounded negative battery. Relay 103 energizes over this circuit and at springs 60 138 prepares the impulsing circuit so that the second digit received will be transmitted to the vertical magnet 113. The impulse cam IC in continuing its rotation then transmits four impulses by interrupting the circuit of the relay 101 at the cam spring 6', 65 as explained heretofore. Relay 101 falls back as before, closing a circuit from ground through spring 133 and its break contact, spring 134 and its make contact, spring 138 and its make contact, through off normal spring 190 and its break contact, through conductor 161, through the winding of relay 105, and magnet 113 to grounded negative battery; with the above traced parallel circuit from spring 134 to the motor magnet 70 112 of the pen register PR. Magnets 112 and 113 energize and follow the impulses delivered by the relay 101 and relay 105 energizes on the first impulse and remains energized throughout the impulsing. Magnet 113 upon energizing, raises the switch shaft and wipers one step vertically at which the off normal springs 190 and 191 are shifted so that the second impulse to the magnet 113 traverses a circuit including the 75 off normal spring 190 and its make contact, conductor 162, spring 140 and its make contact, thence through the winding of relays 105 and magnet 113 to grounded negative battery. After the fourth impulse of a digit 80 has been transmitted the impulse cam IC permits the impulse spring 6' to close the circuit of relay 101 for a relatively longer interval, during which time the circuit of relay 105 is held open at the spring 133 of 85 90 95 100 105 110 115 120 125 130 relay 101, causing the relay to restore to prepare the impulsing circuit so that the next digit will be transmitted to the rotary magnet 114. The impulse cam IC continuing in its rotation interrupts the circuit of relay 101 at impulse spring 6', to transmit two impulses, the last digit of the call number of station A. Relay 101 falls back, as before, closing a circuit traceable from ground to spring 133 and its break contact, spring 134 and its make contact, spring 138 and its make contact, off normal spring 190 and its make contact, conductor 162, spring 140 and its break contact, conductor 168, through springs 141, through the winding of relay 107, through the winding of magnet 114 to grounded negative battery. Relay 107 energizes on the first impulse and remains energized throughout the digit, magnet 114 follows the impulse and advances the shaft carrying the wipers 171-173, inclusive, into engagement with the bank contacts 194-196, inclusive. Relay 107, upon energizing, closes a circuit from ground through spring 149 and its make contact, through the winding of relay 108, to grounded negative battery. Relay 108 energizes and at spring 150 prepares a circuit for relay 106. When the impulse cam IC comes to rest after transmitting the second impulse of the digit, with the impulse spring 6' closed, the circuit of line relay 101 being permanently closed, relay 107 falls back after an interval and, at spring 149, closes a circuit from ground through spring 149 and its break contact,

through spring 150, over conductor 170, through the winding of relay 106 to grounded negative battery. Relay 106 energizes. Relay 106 at spring 144 closes a circuit from ground through spring 144, through conductor 169 and wiper 148 now in engagement with the second bank contact, wiper 173, now in engagement with bank contact 196, through the signal lamp 177 to grounded negative battery, lighting the light to notify the central station attendant that the call came from the station A. Relay 106 at spring 143 closes a circuit from ground through spring 143, conductor 158, signal lamp 159, through springs 132 of the key K^c, conductor 157, through the winding of relay 115 to grounded negative battery, energizing the relay 115 and lighting the signal lamp 159. Relay 115 closes the obvious night alarm circuit at spring 153, energizing the night alarm to give an audible signal to the central station attendant, informing him of the call.

If, for any reason, the central station attendant desires to talk to the patrolman, he operates the key K^c which connects the relay 116 to the line conductors 13 and 15 through condensers 151 and 152; removes the receiver 119 from the hook switch 118, thereby throwing his telephone into operating position so that he may converse with the patrolman. Central station attendant's telephone receives its battery feed from the relay 116 over the obvious circuit; and the substation 33 A receives its battery feed from the windings of relay 101 over the previously traced circuit including the winding 4 of the induction coil and the transmitter 2, these two circuits being connected together by condensers 151 and 152 through which the alternating currents of speech readily pass in the well known manner. Operation of the key K^c, interrupted at spring 132 the above traced circuit including lamp 159 and its relay 115, extinguishing the lamp and allowing the relay to restore and silence the night alarm.

When the conversation is finished the central station attendant restores the receiver 119 to the hook switch 118, thereby interrupting the circuit of relay 116, and restores the key K^c to normal. The patrolman at the station replaces the receiver 1 on the hook switch 3 which interrupts the previously traced circuit for the relay 101, which restores and opens the circuit of relay 102. Relay 102 restores after a brief interval, closing a circuit traceable from ground, through spring 133 and its break contact, spring 134 and its break contact, thence over parallel circuits, one over conductor 160, through off normal springs 146 of the auxiliary switch S, through the winding of magnet 111 to grounded negative battery, and the other through off normal springs 191 of

the control switch C, through the winding of release magnet 109 to grounded negative battery. Release magnets 111 and 109 energize and restore the auxiliary switch S and the control switch C to normal in the well known manner. Relay 102, upon deenergizing, opens the springs 135, removing ground from release trunk conductor 14, thereby breaking the locking circuit of the relay 106 which restores and extinguishes the signal 159, and the signal 177. When the ground is removed from the release trunk conductor 14 the winding 19 of the line switch R deenergizes, permitting the plunger to restore and break the bank contacts 57-60, inclusive, thereby restoring all the equipment to normal, in readiness for the next call.

In the operation of such a police registering system, it may be necessary for the central station attendant to get in communication with the patrolman to advise him of some emergency requiring his attention. To do this, the central station attendant operates the key K¹ to momentarily isolate the line switch R from the lines 7 and 8, and to connect these lines to the desk equipment DE through the medium of the relays 22 and 23. Operation of the key K¹ closes a circuit from ground through springs 43 and its break contact, conductor 73, through the springs 30, the signal lamp 69 to grounded negative battery, lighting the lamp which serves to supervise the call. The operation of key K¹ closes a circuit traceable from ground, through spring 36 of the key K¹ and its make contact, conductor 16, through the motor 71, to grounded negative battery, starting the motor in motion to drive the generator 72 and the interrupter cam 70. The interrupter cam revolves in the direction indicated by the arrow and after an interval closes a circuit from ground through the interrupter cam 70 and its associated cam spring, through spring 35 of the key K¹, conductor 77, through spring 42, through the winding of relay 23, to grounded negative battery. Relay 23 energizes, and at springs 40 and 41 closes a circuit from one pole of the generator 72, through spring 41 and its make contact, conductor 74, through spring 31 and its make contact, line 8, through the hook switch, resistance unit condenser and lamp of all the substations on the line 8 in parallel to the line 7, through spring 34 of the key K¹ and its make contact, conductor 76, through spring 40 and its make contact, to the opposite pole of the generator. Alternating current is projected over the above traced circuit to light the signal lamps 62-65, inclusive, thereby notifying the patrolman that he is wanted. After an interval the interrupter cam 70 opens the above traced circuit for relay 23, which falls back and interrupts the above signalling circuit. In this manner the signal

lamps on the lines 7 and 8 are flashed on and off at intervals under the control of the interrupter cam 70, continuing until the patrolman answers the call. When the patrolman notices the signal he goes to one of the stations on the line, such as A and answers the call by removing the receiver 1 from the hook switch 3, during the interval when the signal lamp 62 is extinguished, thereby closing a circuit traceable from ground through the upper winding of relay 22, through spring 40 and its break contact, conductor 76, spring 34 and its make contact, conductor 7, through the winding 4 of the induction coil of the station A, through the impulse spring 6', the transmitter 2 and the hook switch 3 of the station A, to conductor 8, through spring 31 and its make contact, conductor 74, through spring 41 and its break contact, through the lower winding of relay 22 to grounded negative battery. Relay 22 energizes over the above traced circuit and at spring 42 interrupts the above circuit for relay 23, thereby preventing its subsequent energization, and preventing additional impulses of signal current from being transmitted to the calling line. Relay 22, upon energizing, closes the circuit from ground through spring 43 and its make contact, through spring 46 and its break contact, through the signal lamp 66 to grounded negative battery, lighting the signal lamp 66 and extinguishing the signal lamp 69 which had been lighted through spring 43 and its break contact. The central station attendant then knows that the patrolman has answered the call and he connects in his telephone by operating the key K² and then removing the receiver of the telephone. The transmitter of the desk equipment telephone receives its battery over a circuit from ground, through the upper winding of relay 22, through spring 44 and its make contact, through the transmitter, receiver and hook switch of the desk telephone, through spring 45 and its make contact, through the lower winding of relay 22 to grounded negative battery. When the central station attendant and the patrolman have completed their conversation each restores his receiver to its switchhook, thereby breaking the circuit to relay 22 and allowing it to restore. To restore the central station equipment to normal the attendant must also restore the keys K¹ and K² to normal. If he should fail to do this the signal lamp 69 will be lighted as soon as the relay 22 restores, over the circuit previously traced, and signal current will again be projected over the line as explained hereinbefore. When the attendant restores keys K¹ and K² he extinguishes all signal lamps and reconnects the lines 7 and 8 to the individual line switch R, restoring all the equipment to its normal condition.

If the desk equipment comprising relays 22 and 23, should be out of order or in use by the central station in calling another line, the key K² can be operated to call the patrolman at station A, through the medium of the relays 21 and 20, which are duplicates of relays 22 and 23. The operation in this case is identical with that just explained and need not be repeated.

Having thus described my invention, what I consider new and desire to have protected by Letters Patent is pointed out in the appended claims.

What is claimed is:

1. In a registration system, a central station, a plurality of lines terminating therein, reporting stations on said lines, a control switch at said central station, having a plurality of wipers, a plurality of signals accessible to said switch through said wipers, means automatically operable in response to the initiation of a call from one of the reporting stations for connecting that station to said control switch, an auxiliary switch associated with said control switch and controlled from said reporting stations to select a particular one of said wipers, and means thereafter operable and controlled from said station to cause the control switch to operate said wipers and through said selected wiper operate the signal corresponding to said reporting station.

2. In a registration system, a central station, lines terminating therein, reporting stations on said lines, a control switch, a plurality of signals accessible from said control switch, a pen register associated with said control switch, means responsive to the initiation of a call from one of said reporting stations for connecting that station to said control switch and means for operating said control switch and register to respectively operate the signal corresponding to, and to record the number of the reporting station.

3. In a registration system, a plurality of lines having common access to a control switch, reporting stations on said lines, signals accessible to said control switch, means operable from said reporting stations, for seizing said control switch and operating it to select a signal corresponding to a calling reporting station to make a report, a telephone, common to said switches, means for associating said telephone with the control switch to enable supervision of the call irrespective of the line and station from which it is sent, desk equipment comprising talking and signalling equipment accessible to said line at a point ahead of said control switch, and means at said point for connecting said desk equipment to said line and disconnecting said control switch.

4. In a registration system, a plurality of reporting stations on a common line, said

line terminating in a central station, desk equipment comprising talking and signalling instrumentalities, a key in said line operable to associate the line with the desk equipment, a signal at each reporting station, means in the desk equipment for actuating all of the signals on said line, and means for automatically disconnecting the signalling means and for preparing talking circuits when the patrolman answers the call from any station on the line.

5. In a registration system, a plurality of lines each containing reporting stations, impulse transmitting means at said reporting stations, a control switch common to and accessible from said lines, means responsive to the initiation of a call from a reporting station for connecting the line containing that reporting station to the control switch, 20 a plurality of wipers on said control switch, a plurality of signals accessible to said control switch through said wipers, an auxiliary switch associated with said control switch, means responsive to the first digit transmitted from said reporting station for 25 positioning said auxiliary switch to select one of said wipers, means responsive to the next two digits for positioning the control switch to associate certain of said signals with the control switch and means automatically operable at the completion of the 30 transmission of the last of said digits to operate the signal associated with said selected wiper.

35 6. In a registration system, a line containing reporting stations, an impulse transmitting device at each reporting station and individual thereto, said device being arranged to transmit a code of impulses individual to that station, a central station, line switches 40 at said station on which said lines individually terminate, a control switch accessible to said line switches, signal lamps one for each reporting station on said line accessible to said control switch, a recording device 45 associated with said control switch, said line switch responsive to the initiation of a call from one of said reporting stations to connect that line to the control switch and means responsive to impulses transmitted by said transmitting device at said reporting 50 station, for simultaneously setting said control switch in a position to operate the signal corresponding to the reporting station and operating said recording device to register its individual code.

55 7. In a registration system, a central station, a plurality of lines each terminating in an individual line switch at said central station, reporting stations on said lines, a switch and an impulse transmitting device at each one of said reporting stations, a plurality of control switches accessible to said line switches, a plurality of signal

lamps one for each of said reporting stations accessible to said control switch, means responsive to the operation of one of said reporting station switches for operating said line switch to seize said control switch, and means responsive to impulses transmitted by said impulse transmitting device at one of said reporting stations to operate said control switch to light the one of said signal lamps corresponding to the reporting station from which the impulses were sent. 65

8. In a registration system, a line, reporting stations on said line, a central station, a non-numerical switch in said line at said central station, a control switch accessible to said non-numerical switch and operable by a calling reporting station to record said station on a plurality of indicators, desk equipment comprising talking and signalling instrumentalities accessible to said line, and means on said line at said central station for variably connecting said line to said control switch or said desk equipment. 80

9. In a registration system, a central station, lines terminating therein, a plurality of reporting stations on said lines, a control switch at said central station operable to register a calling reporting station, desk equipment comprising talking and signalling means at said central station, and means operable in each of said lines for connecting said lines with said desk equipment and disconnecting said control switch. 90

10. In a registration system, a central station, a plurality of lines terminating therein, a plurality of reporting stations on each of said lines, a control switch having a plurality of wipers at said central station, an auxiliary switch associated with said control switch for selecting a particular one of said wipers, a signal individual to each reporting station and accessible to said control switch wipers, means automatically operable in response to the initiation of a call from one of the reporting stations for connecting that station to said control switch, and means thereafter operable to cause the auxiliary switch to select one of said wipers and the control switch to select and through said selected wiper operate the signal corresponding to the reporting station. 105

11. In a registration system, a plurality of lines, a plurality of reporting stations on each of said lines, a central station, a control switch at said central station accessible to said lines, a plurality of signals, one for each of said reporting stations, accessible to said switch through a plurality of wipers thereof, an auxiliary switch associated with said control switch for selecting a particular one of said wipers, means responsive to the initiation of a call from one of said report- 120 125

ing stations for connecting said control switch therewith, means controlled from said station for operating said auxiliary switch to select a particular wiper and subsequently 5 to operate said control switch to select a lamp over said selected wiper corresponding so said reporting station, and a register de- vice associated with said control switch, operated simultaneous therewith and with said auxiliary switch to permanently record 10 the number of said reporting stations.

In witness whereof, I hereunto subscribe my name this 4th day of June, A. D., 1925.

CLARENCE E. LOMAX.
